(57) **CLAIM**

The ornamental design for a scooter, as shown and described.

DESCRIPTION

The file of this patent contains at least one drawing/photograph executed in color. Copies of this patent with color drawing(s)/photograph(s) will be provided by the Office upon request and payment of the necessary fee.

Figure 2.1 is a right side elevational view of the scooter embodying the new design;

Figure 2.2 is a right side perspective view of the scooter. The broken lines depict boundaries around the de-emphasized elements, which illustrate portions of the scooter that form no part of the claimed design.
